UNITED STATES PATENT OFFICE.

GEORGE G. WORSTALL, OF TOMS RIVER, NEW JERSEY.

AUTOMATIC LENS-DRILLING ATTACHMENT.

1,222,506.

Specification of Letters Patent. Patented Apr. 10, 1917.

Application filed May 23, 1916. Serial No. 99,418.

To all whom it may concern:

Be it known that I, GEORGE G. WORSTALL, a citizen of the United States, residing at Toms River, in the county of Ocean and State of New Jersey, have invented a new and useful Automatic Lens-Drilling Attachment, of which the following is a specification.

The present invention is a lens drilling attachment for a lathe such as used by watch makers and oculists, and aims to provide a novel and improved device of that nature having means for holding a lens and for adjusting it, in order that an aperture can be drilled at the proper point of the lens for the attachment of the bridge, the present device being especially intended for drilling the lenses of eye glasses or spectacles.

It is the object of the invention to provide an attachment of the character specified of comparatively simple and inexpensive construction, which can be conveniently used upon a lathe for drilling an aperture in a lens, the device having means for the adjustment of the lens, and for advancing the lens against the drill and for retracting it.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:—

Figure 1 is a side elevation of the device. Fig. 2 is another elevation thereof looking at right angles to the line of view in Fig. 1.

Fig. 3 is a sectional detail taken on the line 3—3 of Fig. 1.

Fig. 4 is a sectional detail taken on the line 4—4 of Fig. 2.

Fig. 5 is a view of the lens holding pins and the collar applied to one of them to hold the lens in an oblique position.

In carrying out the invention, there is employed a tail stock sleeve 1 supported by the lathe in the usual or any suitable manner, and having fitted therein for sliding movement a tail stock spindle 2. This spindle 2 is advanced and retracted for moving the lens likewise, and for this purpose, a clamp 3 comprising a doubled strip em-

braces the sleeve 1 and has a clamping bolt 4 engaged through the outstanding ends thereof, a nut 5 being threaded upon the bolt, whereby when the nut is tightened, the terminals of the clamp 3 will be forced toward one another, thus causing the band of the clamp to tightly embrace the sleeve 1, it being preferable to provide a piece 6 of chamois or other suitable material upon the sleeve 1 within the clamp 3 whereby the clamp when tightened will be firmly held in place. By loosening the nut 5, the clamp 3 can be adjusted upon the sleeve 1. A link 7 has one end pivotally engaged upon the bolt 4 between the terminals of the clamp 3, and has pivoted to its other end one end of a lever 8, which is provided with a yoke or loop 9 surrounding the spindle 2 and pivotally engaged therewith, as at 10, whereby the lever 8 which crosses the spindle 2 can be swung by the hand for advancing or retracting the spindle, the link 7 providing a rocking fulcrum for the lever.

The spindle 2 is provided with a reduced terminal or lens rest 11 provided with an axial drill receiving bore 12, and a diametrical bore 13 intersecting the bore 12 to enable the chips or glass dust to pass out of the bore 12. Mounted for longitudinal and angular adjustments upon the terminal 11 is a block or head 14 having a set screw 15 to bear against the terminal 11 for holding the block 14 in any adjusted position, said set screw when loosened permitting the block 14 to be adjusted longitudinally upon the spindle 11 or to be rotated thereon to the desired angular position. The block 14 has a lug or extension 16 projecting outwardly therefrom parallel with the spindle 2, and projecting beyond the terminal 11 of the spindle.

The block 14 carries the means which is used for holding the lens, and for this purpose, a pin 17 extends through the lug 16 and is adapted to rotate therein, and a pair of parallel guide rods 18 are attached rigidly at certain ends to the ends of the pin 17 at the opposite sides of the lug 16. A transverse slide or cross bar 19 is slidable upon the rod 18, and is offset between the rods away from the lug 16 to accommodate the block 14 and terminal 11 of the spindle 2. The slide 19 is provided adjacent the ends thereof with outstanding pins 20. A second slide or cross bar 21 is slidable upon the rods 18 farther remote from the block

14, and has sleeves 22 surrounding the rods 18, to assist in guiding the guide 21 for rectilinear movement. The cross bar 21 is provided adjacent its ends with outstanding pins 23, similar to the pins 20.

15 A collar 24 is adapted to be slipped upon either of the pins 23, for holding the lens L in an oblique position.

16 Coiled wire expansion springs 25 surround the rods 18 and are confined between the cross bar 19 and those ends of the rods 18 which are secured to the pins 17, tending to move the cross bar 19 away from the block 14. Similar springs 26 are disposed upon

15 the rods 18 between the sleeves 22 of the cross bar 21 and the free ends of said rods which are provided with apertures 27 for the reception of the respective ends of the springs 26. The springs 25 are weaker than 20 the springs 26, whereby the tension of the springs 26 overcomes the tension of the springs 25 in order that the lens L will be moved toward the lug 16 when the lens is applied to the cross bars.

25 An adjusting screw 28 is threaded through the lug 16 at right angles with the spindle 2, and has a lock nut 29 thereon to bear against the lug 16 to hold the screw at any adjustment.

30 In using the attachment, supposing the sleeve 1 to be applied to the lathe, and the other parts assembled, the cross bars 19 and 21 are separated and the lens L is placed against the cross bars between the pins 20 and 23. It will be obvious to one skilled in

35 the art that the device can be readily attached to a lathe by applying the sleeve 1 to the rail stock, clamp or other holder of the lathe so that the rotating drill of the lathe 40 lies in a line coaxial with the spindle 2 which is movable toward and away from the drill. The sleeve 1 can be supported in any suitable manner to hold the device in position for coöperating with a drill, and the device need not be used solely on a lathe.

45 After the lens is properly positioned upon the cross bars, the springs 26 will force the cross bars and lens toward the block or head 14 to thereby move the end of the lens past 50 the terminal of the spindle 2. It will be noted that the rods 18 can be swung relative to the block 14 to facilitate the application of the lens to the device. By loosening the lock nut 29, the screw 28 can be adjusted to 55 either move the lens L away from the lug 16, or to permit the lens to move closer to said lug, whereby to adjust the lens to the proper position for drilling. The set screw 15 is then loosened, and the block 14 adjusted

60 to bring the lens rest or terminal 11 of the spindle 2 in such a position that the lens will contact therewith at the point to be drilled, and the lever 8 can then be swung to 65 advance the spindle 2 whereby the lens is carried against the drill (not shown) so that

the drill will drill an aperture in the lens. The bore 12 receives the drill when it penetrates the lens, and the lever 8 can then be moved to retract the spindle and lens. The cross bars 19 and 21 being spring pressed 70 toward one another will clamp the lens therebetween, and the springs 26 being stronger than the springs 25 will move the lens toward and against the adjusting screw 28, and by adjusting said screw, the lens will 75 be carried to the proper position for drilling, thus providing a convenient and practical arrangement.

When it is desired to drill the aperture A of the lens L either above or below the longitudinal axis a of the lens, the collar 24 is applied to the proper pin 23, so that the lens L rests against said collar 24 instead of resting against the pin 23, and this will serve to hold the lens in an oblique position, as 80 seen in Fig. 5, whereby the aperture will be drilled to one side of the axis a of the lens. The collar 24 being applicable to both pins 23, enables the aperture of the lens to be drilled either above or below the longitudinal 85 axis.

Having thus described the invention, what is claimed as new is:

1. A lens drilling device embodying guiding means, adjusting means for a lens, a pair 95 of lens holding members movable along the guiding means, spring means for moving one of said members away from the adjusting means, and spring means for moving the other member toward the adjusting means, 100 said spring means moving said members toward one another, and the second mentioned spring means being of greater tension than the first mentioned spring means to move said members and the lens carried thereby 105 toward the adjusting means.

2. A lens drilling device embodying a head, a lens adjusting screw carried thereby, guide rods pivoted to said head, a pair of lens holding members slidable upon said 110 rods, and spring means for moving said members toward one another and for moving them toward said adjusting screw.

3. A lens drilling device embodying a head, an adjusting screw carried thereby, 115 guide rods connected to said head, a pair of lens holding members slidable upon said rods, spring means for moving one of said members away from the adjusting screw, and spring means for moving the other member 120 toward the adjusting screw, said spring means moving said members toward one another and the second mentioned spring means being of greater tension than the first mentioned spring means to move said members 125 when holding a lens toward the adjusting screw.

4. A lens drilling device embodying a spindle having a lens rest, a head adjustable thereon, guiding means pivotally connected 130

with said head, and lens holding means carried by said guiding means for adjustably supporting a lens.

5. A lens drilling device embodying a spindle having a lens rest, a head adjustable thereon having an outstanding lug, an adjusting screw carried by said lug, a pair of guide rods pivotally connected with the head, a pair of lens holding members slideable upon said rods, spring means for moving one of said members away from the adjusting screw, and spring means for moving the other member toward the adjusting screw, said spring means moving said members toward one another and the second mentioned spring means being stronger than the first mentioned spring means to move said members when holding a lens toward the adjusting screw.
- 15 6. A lens drilling device embodying a tail stock sleeve, a spindle slideable therein, means

carried by the spindle for holding a lens, a clamp embracing said sleeve, a lever engaged with said spindle, and a link connecting said lever and said clamp to provide a rocking 25 fulcrum for the lever.

7. A lens drilling device embodying a pair of members movable toward and away from one another, and each having a pair of pins, said pins being adapted to hold a lens, and 30 a collar adapted to be fitted on certain of said pins for the engagement of the lens whereby the lens will be held in an oblique position.

In testimony that I claim the foregoing 35 as my own, I have hereto affixed my signature in the presence of two witnesses.

GEORGE G. WORSTALL.
